UNITED STATES PATENT OFFICE.

WILLIAM H. BURK, OF ST. LOUIS, MISSOURI, ASSIGNEE TO CORRUGATED PLATE COMPANY, OF ST. LOUIS, MISSOURI, A CORPORATION OF MISSOURI.

SPACING DEVICE FOR REINFORCING-BARS.

1,943,196.

Specification of Letters Patent.

Patented Nov. 5, 1933.

Application filed January 25, 1931. Serial No. 604,625.

To all whom it may concern:

Be it known that I, William H. Burk, a citizen of the United States, and a resident of the city of St. Louis and the State of Missouri, have invented a new and useful improvement in Spacing Devices for Reinforcing Bars.

My invention relates to reinforced concrete structures in which a plurality of 10 metallic bars are arranged in groups in parallel rows, substantially in the same plane or in parallel planes, for strengthening purposes, as for example in girders and panels, and consists in an improved 15 spacing device for supporting and positioning the reinforcing bars in the form in the process of construction.

My improved spacing device has for another object the production of a mechanical 20 connection of considerable rigidity between the reinforcing bars.

A further object of my invention is the production of a spacing device which can be made cheaply from sheet steel or sheet iron 25 such as can easily be obtained on the market, and one which can readily be shipped without liability of injury from careless handling.

A further object of my invention is the 30 production of a spacing device which can be made up at the factory in lengths convenient for handling and which can easily be cut to the proper length at the place where used to suit the requirements of the 35 particular work in hand.

Referring to the accompanying sheet of drawings in which like numerals are used to designate like parts throughout the views; Figure 1 is a fragmentary view showing the stamping from which my device is 40 formed before being bent up; Fig. 2 is a fragmentary top view of my spacing device, with a reinforcing bar shown in position therein, as it would appear when set up in a form ready for filling in the concrete; Fig. 3 is a section on the line 3-3 of Fig. 2 showing one serrated flange in elevation and the reinforcing bar in section; Fig. 4 is a cross section of my device on line 45 4-4 of Fig. 2 showing a fragmentary portion of a reinforcing bar in side elevation.

In constructing the particular form of my spacing device shown in the drawings, I stamp from sheet metal a blank 11, having

serrated edges forming protuberances 12, 55 and openings 13 therein of such configuration that a tongue or lip 14 is formed projecting from one side of the opening at about the median line of the blank, as shown in Fig. 1. This blank is then bent on 60 itself along its median line, 1-1, until it takes a form substantially V shape in cross section as shown in Fig. 4. The relative proportions of the opening 13 are such that in the bent up form there is formed a notch 65 in the top edge of the spacing device sufficiently deep to take a reinforcing bar 20 so that the upper edge of the bar will lie below the upper edge of the spacing device, and the lip 14 will project over the upper 70 edge of the bar and hold it securely in position. If lip 14 be projected at an angle to the side of the opening it will be found possible to insert the bar into the notch and under the lip by swinging it in a horizontal 75 plane until its longitudinal axis is about parallel to the direction in which the lip projects and then springing it into place.

In practice, two or more spacing devices are arranged in the form in which the 80 girder or slab is to be cast, with the flanges resting on the bottom of the form and the notched edge uppermost, transversely to the direction of the length of the reinforcing bars, and at such an angle thereto that the 85 reinforcing bars may readily be dropped upon them and sprung into engagement with the notches under the lips, after which the spacing devices are swung around to lie substantially at right angles to the bars. 90

The notches 13 are spaced longitudinally along the spacing device to position the bars at the desired distance apart. The length of the protuberances 12 is made such that when the blank is bent up into the spacing 95 device the lower edges of the notches 13 will be at such a distance above the form in which the spacing device rests that the reinforcing bars will be spaced at the desired height above the form.

As many spacing devices may be used as is necessary to properly support and space the reinforcing bars in the form.

Thus it is seen that my spacing device is not only cheap to construct and easy to 105 handle, but lends itself readily to expeditious assembling in the forms at the place of use, and provides secure means for spac-

ing the reinforcing bars in parallel relationship in the forms and at the proper distance above the bottom thereof.

What I claim as my invention and desire 5 to secure by Letters Patent is:

1. A supporting and spacing device for reinforcing bars in parallel series, said device comprising a strip of sheet metal having the extremities of its longitudinal margins lying in parallel lines bent along the median line to substantially V-shape, the extremities of said margins thereof being arranged to lie in a plane parallel with the median bend thus formed and form supports for said device, spaced openings along said bend, said openings extending the same distance from the said median line on either side thereof whereby a series of spaced notches is provided along the bend at equal 15 distances from the plane of support, the length and width of the openings being so proportioned that the notches thus formed are slightly wider than a reinforcing bar and of substantially the same depth, and 20 tongues projecting into said openings, said tongues being positioned at the median line of the strip and extending transversely thereto in a plane through the apex of the bend and parallel to the plane of the extremities of the margins of the strip, said 25 tongues being adapted to overlie reinforcing bars positioned in said notches at right angles to the longitudinal axis of the de-

vice, the width of the prongs being such that when the spacing members and reinforcing bars are in such relative position that the prongs extend in a direction parallel with that of the reinforcing bars the latter may be slipped into or out of the notches without distorting the prongs. 35

2. In a metal reinforce for concrete structures, the combination of parallel reinforcing bars with transversely arranged supporting and spacing members, said spacing members being provided with notches 40 along their upper edges slightly wider than the reinforcing bars and of substantially the same depth, and prongs projecting from the upper edges of the spacing members along their median line at nearly right 45 angles thereto and parallel with the plane of the reinforcing bars, the width of the prongs being such that when the spacing members and reinforcing bars are in such relative position that the prongs extend in 50 a direction parallel with that of the reinforcing bars the latter may be slipped into the notches without distorting the prongs, whereupon the spacing members may be 55 swung around until they cross the reinforcing bars at right angles and the prongs 60 will then overlie the bars.
